ATTORNEY

UNITED STATES PATENT OFFICE.

JAMES E. HITCHCOCK, OF TORRANCE, CALIFORNIA.

DRILL BIT WITH REMOVABLE BLADES.

Application filed October 1, 1924. Serial No. 740,956.

My present invention is a drill bit especially suitable for use in the drilling of deep wells, or the like; and it is an object of this invention to provide means permitting the 5 employment of a removable or renewable cast blade or blades in a rotary drilling organization, the mentioned blade or blades being preferably formed of an exceptionally hard material, such as manganese steel or 10 another special steel too hard to be conveniently forged and so formed as to require no machine work. Each blade is preferably provided with novel means for its removable retention in a slotted bit body.

15 As intimated, it is an object of this invention to provide a rotary drill bit with an easily replaceable blade, which may be of the fish-tail type, formed of such hard material and so designed as to assure its wear 20 resistance and its efficient cutting for long periods of time, without necessitating the usual frequent interruptions for resharpening; and an advantageous embodiment of 25 my invention may comprise a blade cast in such form that its cutting edges may be sharpened or resharpened by mere grinding. A special head or retaining portion is preferably cast integral with each blade; and each blade may be provided with means for 30 engagement by a dog or other latching or retaining element, which may be seated or housed in the co-operating bit body, which may be slotted to receive the same.

35 The usual threaded pin, associated with a flat shoulder, being unduly liable to wear and to accidental damage, it is a further object of this invention to provide a construction obviating or minimizing the frequent screwing and unscrewing of threaded pins, 40 and, in a preferred embodiment of my invention, I may employ a sliding connection between a head or expanded portion of each replaceable cast blade and a permanent bit body, the above mentioned latching element, 45 when employed, being housed either in said blade or in said body and provided with means, such as an aperture adapted to be engaged by a pin or wedge, permitting its withdrawal at will, or as may be required for 50 the removal of a worn blade, to be reground or replaced.

It is a further object of my invention to provide an organization substantially as above described not only with a removable

terminal blade, for increasing the depth of 55 a well hole, but also with a lateral blade or blades, adapted to serve as gauging cutters or reamers, effective to bring a hole to a predetermined diameter, all of the mentioned blades being advantageously thick- 60 est at the inner or securing ends thereof, whether wedge-shaped or provided with T heads to facilitate their retention in suitable slots, and any or all of said blades may be subdivided or notched in such manner as to 65 form interrupted cutting edges, the cutting edges left standing between the mentioned notches being preferably offset or relatively staggered, in a manner favorable to their co-operative and mutually supplemental ac- 70 tion.

It is a further object of this invention to provide a blade-holding bit body with a novel arrangement of ducts and grooves for the efficient circulation of a lubricating mud, 75 or the like.

It is also an important general object of this invention to provide a drilling organization comprising separate blades such as may actually be replaced at a cost less than the 80 cost of resharpening an ordinary bit, the difference in cutting effect and the lengthening of the interval between withdrawals thus representing a net gain,—which may amount to thousands of dollars saved in the 85 sinking of a single well.

Other objects of my invention will appear from the following description of a preferred embodiment thereof, taken in connection with the appended claims and the accompanying drawings, in which—

Fig. 1 is an elevational view of my novel drill bit.

Fig. 2 is a substantially median section, showing a simple type of locking device 95 suitable for use therein.

Fig. 3 is an elevational view taken in the direction of the arrow 3 of Fig. 1, with parts broken away.

Fig. 4 is a sectional view, taken as indicated by the line 4—4 of Fig. 1.

Referring to the details of that specific embodiment of my invention chosen for purposes of illustration, 11 may be a blade-holding body, shown as comprising a shank 12 and as terminating at its upper end in a pin 13, for the attachment of the same, an intermediate expanded portion 14 being

upwardly terminated by a shoulder 15, in a usual manner.

Coming now to the novel features of my drill bit, the blade-holding body 11 is provided with a transverse slot 16, shown as expanded at its upper end, to receive the correspondingly expanded and interfitting end 17 of a removable blade 18. The blade 18 may advantageously be cast from manganese steel, or other special steel, and initially provided at its upper end not only with a T-shaped or similar head extending entirely thereacross but with a depression 19 therein, for engagement by a latching dog 20, shown as provided with a spring 21, or by equivalent means, for its releasable retention within the body 11.

Although the lower end of the blade 18, or its equivalent, may be provided with cutting edges of any desired character, I have shown this blade as of fish-tail type, but specialized by providing it with oppositely inclined edges 22, 23, which are interrupted by notches 24 in such manner as to leave complementary sections thereof standing; and it is obvious that the outside diameter of the blade 18, in the region of the cutting edges thereof, should substantially exceed the diameter of the supporting body 11.

When a reaming effect is desired, I may optionally provide the body with additional slots or channels 25, which may be substantially vertical and may be inwardly expanded, as best shown in Fig. 4, in such manner as to adapt the same to the retention of lateral or reaming blades 25^a, the inner ends of these blades being shown as correspondingly expanded, in order to facilitate their removable retention by means such as pins or screws 26; and between the slots or channels 25 I may optionally provide additional lubricating channels 27, to which a lubricant may be delivered from a central passage 28, extending downwardly through the shank 12, by means such as inclined ducts 29, the arrangement here referred to being such as to assure a satisfactory delivery of lubricating mud, or the like, toward both the terminal blade 18 and the lateral or reaming blade or blades 25^a.

It will be understood that either the terminal blade or a pair of reaming blades may be used and replaced independently, the terminal blade shown being specialized for right-hand rotation, and reaming blades being suitable for rotation in either direction; and that the terminal blade, although securely held, may be promptly removed by the insertion of, for example, a pin 30, having an inclined upper edge 31 adapted to cam the dog 20, or its equivalent, against a resilient pressure such as that of the spring 21, into a position permitting the lateral withdrawal of said blade. Blades of

any preferred form may of course be substituted for those shown, but the specific types illustrated are found to co-operate effectively for the purposes indicated.

Although I have herein described my invention in a preferred form, it will be understood that various changes and modifications may be made by those skilled in the art, without the slightest departure from the spirit and scope of my invention, as the same is indicated above and in the following claims.

I claim as my invention:

1. In a drilling organization adapted to operate by rotation and to withstand a torque: a substantially cylindrical blade-holding body provided with lubricant passages and also with a transverse slot distinct from said passages, which slot is widest at its upper end and there forms a T-shaped passage extending entirely through said body to receive a replaceable blade; and a replaceable blade, or fish-tail type, having a cutting edge wider than said body, said blade being formed of cast metal too hard for convenient forging and provided at its inner end with an expanded head slidably interfitting within said slot; interior means, resiliently projected into a depression in said head, for locking said blade in said body; and cam means for releasing said locking means.

2. In a drilling organization adapted to operate by rotation and to withstand a torque: a substantially cylindrical blade-holding body provided with a transverse slot to guide a removable cam pin and with another transverse slot, the latter being widest at its upper end and there forming a T-shaped passage extending entirely through said body to receive a replaceable blade; a replaceable blade, having a cutting edge wider than said body and formed of cast metal too hard for convenient forging, said blade being provided at its inner end with an expanded head slidably interfitting within said last mentioned slot and provided also with means permitting its releasable retention by a locking element; a locking element for said blade, said locking element being disengageable by means comprising a pin movable within said first mentioned slot in said body and having an inclined surface adapting the same to serve as a cam.

3. A drill bit comprising a substantially cylindrical body provided with a T-shaped slot extending therethrough and with means for the releasable retention of a blade slideable in said slot, and provided also with substantially vertical longitudinally extending substantially vertical external channels in its cylindrical surface, some of said channels being adapted to retain independently removable blades, and others of said

channels being connected, by inclined ducts, with a passage for the delivery of a lubricant thereto.

4. A drill bit comprising a substantially cylindrical body having in its cylindrical surface substantially vertical external channels to receive a lubricant, each channel being provided near its upper end with means

for feeding a lubricant thereto; and separate reaming blades supported between and parallel with said channels.

In testimony whereof, I have hereunto set my hand at Los Angeles, California, this 25th day of September, 1924.

JAMES E. HITCHCOCK.
